UNITED STATES PATENT OFFICE.

THOMAS H. BUCKLEY, OF WORCESTER, MASSACHUSETTS.

DESIGN FOR A LUNCH-WAGON BODY.

SPECIFICATION forming part of Design No. 23,011, dated January 23, 1894.

Application filed October 4, 1893. Serial No. 487,182. Term of patent 7 years.

To all whom it may concern:

Be it known that I, THOMAS H. BUCKLEY, a citizen of the United States, residing at Worcester, in the county of Worcester and State of Massachusetts, have invented and produced a new and original Design for a Lunch-Wagon Body, of which the following is a specification, reference being had to the accompanying drawings, forming a part thereof.

10 My invention consists in my new and original design for a lunch-wagon body, as will be hereinafter fully described.

Referring to the drawings: Figure 1 is a perspective front end view of a lunch-wagon body showing my design, and Fig. 2 is a perspective rear end view of a lunch-wagon body showing my design.

The leading features of my design consist in a lunch-wagon body having the shape, configuration, and ornamentation shown in the accompanying drawings. The upper portion of the body, just below the roof, represents panels, and the lower portion is plain, except at the central portion of each side where the panel extends from the top to the bottom. The lower ends of the panels are substantially in the same horizontal line, and the ornamental border is placed around the bottom thereof between the panels and the plain portion.

In the accompanying drawings, the wagon body 1 has a door 2 in each side thereof, with a panel 2' in the upper half thereof, and has an elongated window 3 in the rear portion on one side, and a somewhat shorter window 4, on the opposite side. A series of windows 5, 35 of uniform size, extend entirely around the wagon body in the upper half thereof, except where the doors 2 and the windows 3 and 4 are. These windows or panels are ornamented as shown. By means of the series of windows 5, in connection with the doors 2, and windows 3 and 4, forming the upper portion of the wagon body, a light and airy appearance is given to the wagon body, and the interior thereof will be brilliantly lighted from 45 any exterior artificial light. The ornamental border 6 extends around the body between the panels and the plain portion, as shown in the drawings.

What I claim is—

15 The design for a lunch wagon body, substantially as shown and described.

THOMAS H. BUCKLEY.
